AQUARIUM FILTER

Henry Arak, Brooklyn, N.Y., assignor to The Wil-Nes Corporation, a corporation of New York

Filed June 27, 1960, Ser. No. 61,130

Term of patent 14 years

(Cl. D91—1)

FIG.1

I claim:

The ornamental design for an aquarium filter, substantially shown.
